MOBILE BUILDING STRUCTURE

Richard A. Barlow, Springfield, Va.
(2008 Dundee Road, Rockville, Md. 20850)

Filed Dec. 29, 1971, Ser. No. 213,795

Term of patent 7 years

Int. Cl. D12—10

U.S. Cl. D12—103

Fig. 1

Fig. 2

Fig. 3

Fig. 4

Fig. 5

FIG. 1 is a perspective view of the building structure embodying the design of the present invention as it would appear in its expanded position.

FIG. 2 is a top plan view of the building structure of FIG. 1.

FIG. 3 is a front elevational view of the building structure of FIG. 1.

FIG. 4 is a rear elevational view of the building structure of FIG. 1.

FIG. 5 is a side elevational view of the building structure of FIG. 1, both sides being the same.

I claim:

The ornamental design for a mobile building structure, as shown and described.
